THE NORRIS PETERS CO., WASHINGTON, D. C.

UNITED STATES PATENT OFFICE.

CHARLES E. WILL, OF WATERLOO, IOWA, ASSIGNOR OF ONE-FOURTH TO
FRANK J. EIGHMEY, OF WATERLOO, IOWA.

RAILWAY-TIE.

No. 853,390.

Specification of Letters Patent.

Patented May 14, 1907.

Application filed July 24, 1906. Serial No. 327,482.

To all whom it may concern:

Be it known that I, CHARLES E. WILL, a citizen of the United States of America, and a resident of Waterloo, Blackhawk county, 5 Iowa, have invented certain new and useful Improvements in Railway-Ties, of which the following is a specification.

My invention relates to railway ties and the object of my invention is to provide a tie 10 of such a form as will anchor it in the road-bed, such a tie having a removable locking means for the rails combined with elastic bases for said rails.

The objects above set forth are accomplished by the means which are hereinafter described and claimed, and which are illustrated in the accompanying drawings, in which—

Figure 1 is a plan view of my improved tie 20 with rails attached by means of my special form of locking clutches, Fig. 2 is a side elevation of the same, Fig. 3 is a perspective view of one of the clutch members, Fig. 4 is a perspective view of one of the toothed 25 wedges, and Fig. 5 is another perspective view as seen from the opposite side of the clutch member shown in Fig. 3 depicting it with the toothed wedge inserted in its proper position in the slot between the jaws of said 30 member.

Similar letters refer to similar parts throughout the several views.

The tie *a* may be constructed from iron or any other suitable metal or material which 35 will long resist the corrosive effects of the elements, and is made of a peculiar shape as shown in Fig. 2, which aids in anchoring it *in situ* in the road bed to prevent lateral displacement.

40 The tie has the middle portion of its lower surface cut away to a considerable extent to form an arched recess *g*. The arched recess *g* may be of the form shown or otherwise as desired, its object being to provide opposing 45 faces to the earth inclosed between to prevent sidewise slip. I have also shown upward projections *c* on the upper sides of the ends of the tie where said ends have been cut away to form outwardly sloping grooves *l*. The projections *c* may be of the height shown or otherwise as desired, as the function of such projections is to help lock the tie in place in

such situations as it is embedded in the soil or pavement.

The tie *a* has at proper distances from each 55 end transversely recessed seats *n* whose transverse upper edges are somewhat inclined toward each other and whose base is square to form seats for the elastic blocks *k*, as shown in Fig. 2. The blocks *k* upon which 60 the rails *b* are seated are formed from wood or any other suitable material having a small amount of elasticity.

h, h, are clutch members unconnected but having inwardly directed jaws *d*, said jaws 65 having vertical transversely toothed slots *e* for the reception of the toothed wedges *f*. Each clutch member has a transverse shoulder *o* to engage the inner surface of the recess *n*. The wedges *f* are each provided on one 70 side with a few transverse teeth *m* for a purpose presently to be described.

When the blocks *k* have been fitted within the recesses *n* and the rails *b* seated upon them, the clutch members *h* are driven in 75 from the side so as to be seated between the vertical sides of the blocks *k* and the sides of the recesses *n* with their jaws engaging the base flanges of said rails. The wedges *f* are then driven down through the slots *e* so as to 80 pass between the clutches *h* and the vertical sides of the blocks *k*, the notches or teeth *m* being on the outside and engaging the notches *p* of the slot *d* in each clutch member *a*. If, on account of shrinking or contraction by 85 reason of compression, the blocks *k* become slightly smaller so as to somewhat loosen the clutch members *h* in the recesses *n*, the clutch parts may be easily tightened into effective locking position by simply driving down the 90 wedges *f* to the extent of one or more of the teeth *m*, the engagement of said teeth with the teeth *p* of the slot *e* then locking the clutch in place. The clutch members may be easily disengaged from the rail after the 95 wedges have been withdrawn, if it is desired to substitute a new block *k* for one which has become too much decayed.

It will be seen that my improved tie while composed of but few parts and those easily put in place or removed, can at all times with but little trouble be kept firmly locked to the rails, and as a whole has but a small portion subject to deterioration or decay. The rail

has a sufficiently elastic base formed of a minimum of material.

Having described my invention, what I claim as new, and desire to secure by Letters 5 Patent, is—

1. A railway tie, composed of a body having recessed seats, a removable base-block in each seat, and clutch-members removably secured between said bases and said seats.
- 10 2. A railway tie, composed of a body having recessed seats, an elastic base-block in each seat, and clutch-members removably secured between said bases and said seats.
- 15 3. A railway tie, composed of a body having recessed seats, a removable elastic base-block in each seat, and clutch-members removably secured between said bases and said seats.
- 20 4. A railway tie, composed of a body having recessed seats, an elastic base in each seat, clutch-members having slotted jaws removably secured between said bases and said seats, and wedges inserted in the slots of the jaws of said clutch-members between said members and said elastic bases.
- 25 5. A railway-tie, composed of a body having recessed seats, an elastic base in each seat, clutch-members having slotted jaws removably secured between said bases and said

seats, and wedges toothed on one side and inserted in the slots of the jaws of said clutch-members between said members and said elastic bases, the teeth of said wedges engaging the inner faces of said slots.

6. A railway-tie, composed of a body having recessed seats, a removable base-block in each seat, clutch-members removably secured between said base-blocks and said seats, said tie-body being provided with suitable anchoring means.

7. A railway-tie, composed of a body having recessed seats, an elastic base in each seat, clutch-members having slotted jaws removably secured between said bases and said seats, the inner faces of said slots having downwardly directed transverse teeth, and wedges having upwardly directed transverse teeth on one side, said wedges being inserted in the jaws of said clutch-members between said clutch-members and said bases, the teeth of said wedges engaging and interlocking with the teeth on said clutch-members.

Signed at Waterloo, Iowa, this 20th day of July, 1906.

CHARLES E. WILL.
